UNITED STATES PATENT OFFICE.

FRANK BUCHANAN, OF DAYTON, OHIO.

ELECTRIC-ARC LAMP.

1,083,187.

Specification of Letters Patent. Patented Dec. 30, 1913.

Application filed December 9, 1909. Serial No. 532,244.

To all whom it may concern:

Be it known that I, FRANK BUCHANAN, of Dayton, in the county of Montgomery, in the State of Ohio, have invented new and useful Improvements in Electric-Arc Lamps, of which the following, taken in connection with the accompanying drawings, is a full, clear, and exact description.

This invention relates to certain improvements in electric arc lamps for head-lights and similar purposes and refers more particularly to means for steadyng the action of the feeding clutch for the upper electrode.

The main object therefore is to provide suitable mechanisms for steadyng the action of the armature and also to prevent the transmission of excessive vibration of such armature to the electrode-operating clutch so as to avoid chattering or hammering of the electrode.

Another object is to render the action of the armature more quickly responsive to the energizing of the magnet by making such armature in the form of an opened laminated frame centrally fulcrumed at opposite sides of the magnet and extending entirely around the poles thereof, so as to establish a closed magnetic circuit.

Other objects and uses will be brought out in the following description.

In the drawings: Figures 1, 2 and 3 are respectively a top plan, a side elevation and a front elevation of an arc lamp embodying the various features of my invention. Fig. 4 is an enlarged detailed sectional view through the rocking armature and its connections with the clutch mechanism for the upper electrode taken on line 4-4, Fig. 1. Fig. 5 is an enlarged sectional view taken on line 5-5, Fig. 1, showing the retarding wheel, the ratchet and pawl and train of gears for transmitting motion from the armature to said retarding wheel. Figs. 6 and 7 are enlarged sectional views taken respectively on line 6-6, Fig. 1 and 7-7, Fig. 4, Fig. 7 showing particularly the connection between the armature and clutch and Fig. 6 showing one of the bearings for the armature.

The lamp proper comprises a pair of ver-

tically disposed coaxial electrodes —1— and —2—, meeting end to end within a suitable globe —3—; the lower electrode being adjustable in a suitable guide tube —4— by means of a rotary knurled wheel —5— which is spring pressed through a slot in the tube —4— against the lower carbon —1— and adapted to be rotated by a hand operated spindle —6—, so as to feed the lower carbon up or down as may be desired. The upper electrode —2— is also adjustable vertically in suitable guide tubes —7— and —8— which are spaced some distance apart to receive and permit the operation of a clutch —9— of porcelain or other insulating material. The clutch —9— normally rests upon the enlarged upper end or head —10— of the guide tube —7— and is provided with a vertical opening or slot —11— through which the upper electrode is passed and adapted to move with an easy sliding fit when the clutch is in its normal position, so as to establish contact with the lower electrode. One side of the clutch is spring pressed against the head —10— by a compression spring —12— and its opposite side is pivotally connected to one end of an upright link section —13— which in turn is yieldingly connected to a second link section —14— by means of a spring —15—. The upper portion of the link —13— which is pivotally connected to the clutch —9— is made in the form of a loop having its sides spaced apart and connected at the top by a cross bar which is provided with a central guide opening therethrough, while the link —14— which is pivotally connected to the armature —16— is provided with a reduced stem projecting downwardly through and guided in the aperture in the upper end of the link —13— and terminates at its lower end in an enlarged rectangular shoulder —14'— which fits with an easy sliding fit between the sides of the link —13—, sufficient clearance being left between the shoulder —14'— and cross bar at the end of the link —13— to permit a limited relative endwise movement of the links.

The spring —15— is comparatively light and of just sufficient tension to lift the cor-

100

responding end of the clutch upwardly and thereby grip and elevate the upper carbon to form the desired gap at the meeting ends of the electrodes, the upper link section 5 —14— having sufficient play to permit vibration of the armature without imparting similar vibration to the clutch.

The upper link section —14— is pivotally connected to one side of a rocking armature 10 —16— which is centrally pivoted on the inner ends of adjustable cone bearings —18— formed, in this instance, by the inner ends of adjusting screws —19—. This armature preferably consists of a rectangular open frame within which is located an electro-magnet —20— having its pole pieces lying in substantially the same plane as the axis of the armature, said armature being normally disposed at an angle with the axis 20 of the electro-magnet with its front end nearest the carbon depressed.

The mechanism for retarding the action of the armature and upper electrode connected thereto includes a comparatively 25 heavy balance wheel —21— and brake and suitable means for imparting motion to said wheel from the armature, the brake and inertia of the wheel —21— being sufficient to retard impulsive action of the armature.

30 The means for transmitting motion from the armature to the balance wheel comprises, in this instance, a ratchet wheel —22—, a pawl —23— and a gear train —24— in which the gears are so relatively proportioned as to increase the resistance to the action of the armature in separating the electrodes.

The entire mechanism thus far described is mounted upon an upright rock arm 40 —25— which is provided with a pivotal bearing —26— journaled in an upright supporting frame —27— said rock arm being adjustable about its axis by means of adjusting screws —28—, as best seen in Fig. 2.

45 The screws —19— upon which the armature —16— is mounted are engaged in threaded aperture in suitable bearings —29— forming a portion of the frame —17— which is secured to the upper end 50 of the rock arm —25—.

The ratchet wheel —22— and coaxial gear —24— are connected to rotate together by means of a bushing —30— which turns on the sleeve —31—, said sleeve being held in 55 operative position against turning by a lock nut —32— which is screwed upon the outer end of the screw —19— and presses the sleeve against the outer face of the bearing —29— in which the screw —19— is engaged.

The pawl —23— is pivotally mounted on a stud —33— on the adjacent side of the front end of the armature some distance in front of the axis of the latter and en-

gages the teeth of the ratchet wheel 22 as 65 shown in Fig. 5.

The balance wheel —21— is journaled upon a stud or shaft —35— on a pendant portion of the frame —17— some distance below the swinging axis of the armature and 70 is secured to the coaxial pinion of the gear train —24—. In order that the momentum of the balance wheel may be further retarded I provide a suitable brake shoe or drag —37— consisting of a gravity bar 75 pivoted at one end at —38— to a fixed support —39— and having its other end free to gravitate against the upper face or periphery of the balance wheel, the latter being in this instance provided with an annular groove —40— in which the weighted bar —38— is guided and held against lateral displacement and also affording additional friction bearing for the drag or bar.

The spring —15— is interposed between 85 this shoulder —14— and upper end of the link —13— and is tensioned so as to allow the clutch —9— to gravitate to its normal down position when the armature —16— is in its normal position, or when the electro-magnet is deenergized the front end of the armature being weighted by the links —13— and —14— and clutch —9— which cause said front end to gravitate downwardly under such deenergized conditions. 95

In operation when the electro-magnet is energized the armature —16— is instantly drawn toward a substantially horizontal position. This action of the armature lifts the link —14— and compresses the spring 100 —15— which by its own tension gradually elevates the link —13— and thereby tilts the clutch —9— sufficiently to grip and raise the electrode —2— to form a gap between it and the electrode —1— and thus produce 105 the desired arc. When the links —13— and —14— are thus elevated by the action of the armature and the clutch is tilted to separate the electrode —2— from the electrode —1— the spring —15— is under compression and 110 operates to hold the clutch in its tilted position even though the armature may continue to vibrate under the influence of the energized magnet thereby preventing the transmission of this excessive vibration of 115 the armature to the clutch which in turn prevents the chattering of the upper electrode. Again when the electro-magnet is energized by the closing of the lighting circuit, the inertia of the weighted retarding 120 wheel —21— together with the connections between said wheel and the armature tends to retard and to steady the action of the armature and thereby prevents too rapid movement of the upper electrodes and chattering of the feeding clutch. 125

What I claim is:

In combination with the electrodes of an

electric arc lamp, a feeding clutch for one of the electrodes, an electro-magnet having a rocking armature, connections between said armature and clutch at one side of the 5 electrodes, a ratchet wheel coaxial with the axis of movement of the armature and rotatable independently thereof, a pawl on the armature for engaging and rotating said

ratchet wheel, and means to retard the initial movement of the ratchet wheel.

In witness whereof I have hereunto set 10 my hand this 24th day of November 1909.

FRANK BUCHANAN.
